UNITED STATES PATENT OFFICE.

LORING J. BAKER, OF BOSTON, MASSACHUSETTS.

SELF-LEVELING BERTH.

SPECIFICATION forming part of Letters Patent No. 269,617, dated December 26, 1882.

Application filed May 4, 1882. (No model.)

To all whom it may concern:

Be it known that I, LORING J. BAKER, of Boston, in the county of Suffolk and State of Massachusetts, have invented a new and useful 5 Improvement in Self-Leveling Ships' Berths; and I do hereby declare that the following is a full, clear, and exact description of the same.

My invention relates to swinging berths such as are used on shipboard to automatically adapt themselves to the motions of the ship, and to remain in a horizontal position whether the ship pitch or roll. In berths of this class it is desirable to have freedom of movement with sufficient stability in the berth 15 to allow the occupant to get in and out without difficulty. It is also desirable to occupy the least possible space both for the movement of the berth and for the mechanism which supports it, both on account of the limited space 20 on shipboard and because it is desirable to adapt the apparatus to cabins having the bed or fixed form of berths. It has heretofore been found necessary in many forms of swinging berths to suspend the berth from above in order 25 to obtain the proper swinging movement; but this has encumbered the space above the berth and occasions great inconvenience to the occupant, the supporting mechanism being unavoidably in the way.

The object of my invention is to economize the space both above and below the berth, as well as at the ends, to reduce the mechanism which supports the berth to the simplest possible limits, to secure an easy limited movement, and to provide locking mechanism by 35 which the occupant can at any time lock the berth in any desired position.

My invention consists, first, of improved supporting devices adapted to give proper rocking or swinging movement to the berth; second, in an improved device for limiting the lateral movement and for regulating the longitudinal inclination of the berth; and, third, of an improved locking device for fixing the 45 berth in any given position.

In the accompanying drawings, Figure 1 represents a plan view of my berth; Fig. 2, a rear side elevation, and Fig. 3 a section on line $x x$ of Fig. 1.

In these drawings, A represents the berth, which I have shown as provided with a back,

a , highest at the middle part. The berth is supported directly upon a rod, b , which lies in a transverse groove or any suitable bearing on the under side of the berth. This rod is 55 fixed to side bars, $c c$, which are suspended by yokes $d d$, pivoted to the ends of the side bars. These yokes are made preferably rectangular in form, and are fitted to pass over the ends of the berth and inclose the same, so that they 60 occupy no space between the ends of the berth and the walls; and, further, as the berth rocks and either end rises its upward movement is limited by coming in contact with the horizontal part of the yoke. The yokes are suspended 65 from the end walls by links $e e$. These links are attached to staples in the wall, and also to the yokes by means of elongated staples f . This construction of the side pieces, yokes, and suspending-links allows longitudinal swinging 70 movement of the frame which supports the berth within the end partitions, with a constant tendency to bring the berth back to a central position. It also permits a lateral swinging movement within sufficient limits, 75 and as the links are connected to the yokes at a little distance from each other they tend to restrain the lateral swing of the berth and to return it to a normal position, for the reason that as the berth swings to one side or the 80 other it throws the weight upon the links opposite that side to which it swings, thus changing the position of the support from the center to the side toward which the berth is to be returned.

The devices already described allow all the movement necessary to permit the berth to remain in a horizontal position in the pitch or roll of the ship. In order to maintain the berth in this position, I provide another connection 90 of the berth with some fixed point, whereby the berth is held in its proper relation to the frame.

It will be apparent, as the berth rests only upon the transverse rod, that without some other connection its ends would not be supported, but either one end or the other might tip to the floor. In order to provide such connection and support without interfering with the proper lateral movement of the berth, I have devised a jointed bracket, $g h$, which 95 connects the upper part of the back of the berth at an approximately central point with

the wall of the compartment. The piece *h* is pivoted in ears upon the wall, so as to swing freely in a transverse vertical plane. Upon the free end of it is pivoted the piece or arm 5 *g*, adapted to swing also in a transverse vertical plane. This arm *g* is pivoted at its upper end, as shown in Figs. 2 and 3, to a pin, *k*, the end of which works in a bearing in the back of the berth. This allows the berth to 10 swing laterally within certain limits—that is to say, the berth may swing out until the part *h* of the bracket is brought down to a nearly vertical position; or it may swing inwardly until the two parts of the bracket are extended 15 to the utmost limit of their length. Further, as the arm *g* can move only in a vertical plane across the berth, it prevents any longitudinal movement of that part of the berth to which it is attached and causes the berth to swing 20 longitudinally, as if it were suspended from the pin *k*. Thus the berth has two bearing-points—one upon the transverse rod *b* underneath it and the other at the pin *k*, so that the berth is held in a certain relation to the 25 frame, and can only swing out of horizontal plane with endwise movement of said frame. The bracket is formed with wide bearings upon the piece *h*, in order to guard against the twisting strain which would be put upon it by 30 the longitudinal swing of the berth.

I do not confine myself to this special construction of the bracket, as it may be varied, the essential point in respect to this part of my invention being the upper support, which holds 35 the upper part of the back of the berth (or the upper end of a standard fixed thereto) against longitudinal movement, while permitting free lateral movement.

The position of the pin *k* is represented in 40 the drawings as at a central point in the length of the berth; but in order to adapt the berth to the position of the occupant when a greater weight is thrown upon one end or the other, I have provided a slot for the pin *k*, so that it 45 may be moved out of the center in one direction or the other in order to adapt it to the center of gravity. Thus, if the greater weight of the person be at the head of the berth, the pin has to be shifted toward the head. It may 50 be changed and held in position when changed by means of a thumb-nut, *l*, easily accessible to the person in the berth.

In berths of this class it is desirable to have a simple locking device by means of 55 which the berth may be held in any required position both against longitudinal and lateral movement; that both movements should be prevented by a single device, and that this device should be operative by means of a handle within reach of the occupant. I accomplish all this by means of interlocking serrated plates, one fixed to the wall and the other movable upon the berth. The fixed plate is shown at *m*. It is fixed to the wall and projects at right angles therefrom underneath the 60 berth. The upper edge is curved on a line

parallel with the line of movement of the inner lower corner of the berth. On the inner bar, *c*, is another movable plate, *n*, having a serrated locking-edge, as described. I prefer 70 to pivot it in the manner shown in Fig. 2, the plate being slotted, as shown in that figure, to receive screws which hold it in place and limit its vertical movement. It is moved by a bell-crank lever, *o*, which is connected to 75 the plate *n* by a link, *p*. The bell-crank lever *o* is pivoted upon the back of the berth, and a handle *q* projects over the edge, so as to be conveniently within the reach of the occupant 80 of the berth.

It will be apparent that when the lever *o* is moved in one direction the plate *n* will be pushed downward to interlock with the plate *m*, when the berth will be held against any 85 tilting or rocking movement in either direction. The plates are both made long enough to provide for all the movement of which the berth is capable. This locking-plate, being arranged midway of the berth, holds it steadily and securely in place. The form of the plates 90 and the devices for causing them to interlock may be varied without departing from the spirit of my invention.

Having thus described my invention, what I 95 claim is—

1. In combination, a suspended frame adapted to swing longitudinally and laterally, a berth centrally supported on transverse pivots on said frame, and an upper supporting-pivot on a flexible bracket adapted to hold the berth 100 in proper relation to the frame, substantially as described.

2. In combination, a suspended frame adapted to swing longitudinally and laterally, a berth centrally supported on transverse pivot 105 on said frame, a bracket connected by pivot to a central upper extension of the berth, and also to a fixed part, and inflexible in the direction of the length of the berth, but permitting lateral movement, substantially as described.

3. In combination, a suspended frame adapted to swing laterally and longitudinally, a berth supported centrally on transverse pivot, a jointed connecting-bracket, *g* *h*, and pivot *k*, 115 all substantially as set forth.

4. In combination with the berth supported on a swinging frame, the slotted upper extension, the adjustable pin, and the transversely-flexible bracket, substantially as described.

5. In combination, a berth, side bars, a central transverse pivoting-rod, end yokes suspended from the walls, and an upper transversely-flexible arm carrying a pivot for the upper extension of said berth, substantially 125 as described.

6. In combination, the side bars supporting the pivoted berth, the yokes, and the links *e* *e*, converging toward their lower ends and separately connected to the links, as set forth.

7. In combination with a swinging berth and supporting mechanism, substantially as

described, whereby lateral and longitudinal movement is permitted, a serrated plate fixed to a part outside the berth, a movable serrated plate on the berth at right angles to the fixed, 5 and a lever for operating the movable, plate, substantially as described.

8. In combination with a swinging berth, the plate *m*, fixed to the wall, the plate *n*, movable on the berth, bell-crank lever *o*, and link 10 *p*, all substantially as described.

9. The combination of the side bars, *c c*,

yokes *d d*, links *e e*, bracket *g h*, and pin *k*, all constructed as shown in the described relation to the berth.

In testimony whereof I have signed my name 15 to this specification in the presence of two subscribing witnesses.
